UNITED STATES PATENT OFFICE.

JACOB I. RUSSAKOV, OF CHICAGO, ILLINOIS.

DISPLAY COVER FOR RELATIVELY LONG BOXES.

Application filed July 14, 1924. Serial No. 725,888.

To all whom it may concern:

Be it known that I, JACOB I. RUSSAKOV, a citizen of the United States, residing in Chicago, Cook County, Illinois, have invented certain new and useful Improvements in Display Covers for Relatively Long Boxes, of which the following is a specification.

These improvements relate to readily applicable and removable covers for use upon the open tops of relatively long and narrow boxes so as to display while protective-ly enclosing their contents.

Certain fruits and other commodities such as crackers, biscuits and the like are, to a large extent, shipped by the growers or manufacturers in standard-size boxes approximately twenty-one and one-half inches long by thirteen and one-half inches wide. The store-keeper removes the top boards and thereafter desires to sell the contents directly from the box while keeping the goods on display. It has been suggested heretofore to provide a display cover for such boxes comprising two relatively long and narrow wooden frames of the length of the box and half its width hinged together and having the combined area and shape of the top of the box, each of the frames having a glass panel extending substantially from end to end of the box, one of the frames being secured in a readily removable way to the top of the box, the other frame constituting a door and swing-ing open for access to the commodity.

Another suggestion for the purpose has been to provide two relatively long and narrow sheet-metal frames the length of the box, each having marginal flanges adapted to encompass the outer surfaces of the box near the top, each frame having a glass plate extending from end to end of the box, the frames also being hinged together, with means for securing one of the frames readily removably upon the box, the other frame similarly constituting a door.

In each of these instances the narrow frame constituting the door extends from end to end of the box and provides an opening which is about the length of the box and about half its width. In such construction access to the contents below the relatively fixed part of the cover is fairly difficult, with the result that in practice the commodities are unequally withdrawn, the appearance of the display marred—notably

where the goods, as biscuits, are packed in layers with sheets of paper between them—handling the goods, as fruit, to pick out spoiled items is difficult and often not attended to, and, since such boxes are usually set on a rack inclined downward and away from the front, the uppermost contents fall down upon the lower when relieved of the subjacent support by such withdrawals immediately below the door. Furthermore, the inner surfaces of the relatively fixed glass plate in such instances can not be readily cleaned without removal of the cover complete.

The present improvements have for their principal objects the provision of a display cover for such relatively long boxes according to which free and easy access may be had to all parts of the interior of the box through an opening or openings substantially coextensive with the open top of the box; to provide a cover which may be readily applied and removed, and which holds itself in position on the box firmly and securely; to provide a cover which protects the contents unusually well from dirt, dust and vermin; one which overcomes such disadvantages as hereinabove mentioned; and one which is unusually attractive in appearance—a quality of importance in a device for displaying such commodities. Other objects and advantages will appear herein-
after.

In the accompanying drawings, which form a part of this specification, Figure 1 is a face view of my improved cover with the doors closed, and it may be considered to be shown as applied normally to the box of Fig. 3; Fig. 2 shows the cover of Fig. 1 viewed slightly from the top, and with the doors open; and Fig. 3 is a sectional view as on the line 3—3 of Fig. 1, showing the application of the cover to a box of the character described.

The box 10 illustrates the relatively long and narrow box of commerce hereinabove described. It is deep or shallow according to the commodity enclosed.

My improved display cover is formed largely of sheet metal and may be made according to practices well understood in the art. It comprises first a flat rectangular base comprising relatively long and narrow strip-like side parts 11 and 12 and relatively long and narrow flat strip-like end parts 13 and 14, these parts being prefer-

ably integral with each other and being formed in the shape of the top of the box and adapted to rest upon the top edges of the box defining the opening therein, as 5 well illustrated in Fig. 3. This base defines an open interior which is preferably substantially the area of the open top of the box.

Depending from the outer edge of the base 10 parts respectively are side flanges 15 and 16 (the flange 16 corresponding with the flange 15) and end flanges 17 and 18, these flanges being preferably integral with the base parts and being adapted to encompass and tele- 15 scope upon the outer surfaces of the box at upper portions thereof in readily applicable and removable relation. A bead is turned inward upon the lower edges of the flanges as shown at 20, Fig. 3, which provides a substantially good seal for the cover against the 20 entrance of dust and dirt and creeping vermin, and the fact that the base rests upon the top edges of the box further adds to the protection afforded the contents at this place.

25 I preferably employ also, as an integral part, a relatively long and narrow strip-like member 22 extending from the base part 11 to the base part 12 midway between the ends of the device. This member 22 not only 30 strengthens the base, but forms a rest for the doors and cooperates in the provision of a seal for the device around the margins of the doors. While it divides the opening in the base into two relatively large openings, 35 this strip 22 is so narrow as not materially to alter the effect of an opening in the base substantially coextensive with the open top of the box. It may be omitted, with loss of 40 advantage, while retaining other advantages of the construction.

Upstanding flanges 23, 24, 25 and 26 beaded at the top are formed at the inner edges of the base frame parts, not only further strengthening the base, but providing rounded edges for the openings through which the hand passes, and cooperating also to provide a seal for the door openings.

A pair of doors 27 and 28 are hinged upon the base, preferably at each end of the base, 50 so that the doors will swing outward from the middle and stand open widely to permit free access to the hollow interior of the box through the open interior of the base. The doors respectively comprise integral upper 55 frame parts 30, lower frame parts 31, outer frame parts 32, and inner frame parts 33, and depending from these frame parts respectively are top flanges 34, bottom flanges 35, inner flanges 36, and outer flanges 37. A marginal 60 bead 38 enclosing a wire is at the free edges of the door flanges, and the hinge 40 is substantially a continuation of this bead. When the doors are closed the marginal edges of the door flanges respectively rest flat upon 65 the base parts and the intermediate structure

22, as well illustrated in Fig. 3, and the door flanges surround the upstanding flanges defining the hollow interior of the base through which access is had to the interior of the box.

The frame parts of the doors respectively define a sight-opening therefor which is relatively large, and in preferred practice is so large as to expose substantially all of the top layer of the contents of the box. These sight-openings are covered by transparent material, preferably glass plate, as 42, which may be secured to the doors respectively in any approved way.

I may hinge the doors at the top instead of at the outer ends of the base, although not to equal advantage. Hinging the doors at the bottom would be less advantageous than hinging them at the top, and hinging them in the middle would be less advantageous still. Swinging the doors upon the ends of the base as illustrated provides an unusually free opening, and the operation of opening and closing the doors is particularly simple and convenient in that it calls for much the same character of operation as the opening and closing of a box. The construction illustrated has the further advantage in that one or the other of the doors may be opened without exposing the entire contents at any given time, and yet an equitable withdrawal of the box contents over its entire surface may be conveniently had. The goods within the box are peculiarly well displayed, and the cover as a whole presents an unusually attractive appearance. It may simply be telescoped upon the open top portions of the box, and as easily withdrawn, and is well held in position when in use. Fastening means for the device may be dispensed with. The structure as a whole is strong and light in weight. It affords unusual protection for the goods, and at the same time substantially all of the commodities normally available for display can be viewed through the relatively large sight openings.

The device embodies many advantages readily to be appreciated by those skilled in the art. Its utility and value do not depend strictly upon the features of construction as actually illustrated and as specifically described herein, and I contemplate as being included in the invention such reasonable departures therefrom as are indicated in the appended claims.

I claim:

1. A display cover for a relatively long rectangular open-top box of the character described, comprising in combination a substantially flat sheet metal base of relatively long and narrow side and end parts arranged to conform in shape to the top of the box and adapted to rest upon the top edges thereof, said base having depending con- 120

tinuous flanges adapted to telescope readily upon the box and to hold the base thereon, said base parts defining an open interior substantially the area of the 5 open top of the box, a strip-like support extending from one side base part to the other side base part substantially midway between the end base parts and across said open interior and dividing said open interior into 10 two substantially equal parts, a pair of doors with a relatively large sight-opening in each thereof hinged upon the respective end parts of the base and adapted normally to overlie said parts of the open interior 15 respectively and to open so as to stand entirely away from said open interior, each of said sight openings being covered with substantially transparent material, there being an upstanding continuous flange-like 20 part surrounding each part of the open interior, the doors telescoping respectively with each upstanding flange-like part.

2. A display cover for a relatively long open-top box of the character described, 25 comprising in combination a substantially flat sheet metal base of relatively long and narrow parts arranged to conform in shape to the top of the box and adapted to rest upon the top edges thereof, said base having 30 depending flanges adapted to telescope upon surfaces of the box near the top thereof in readily attachable and detachable relation, there being a substantially flat relatively long and narrow strip-like support 35 extending from one side part of the base to the opposite side part thereof substantially midway between the ends thereof and adapted to lie beneath edges of doors ad-

jaacent to each other when the doors are in closing position, said base parts and said strip-like support defining two door openings having a combined area substantially close to that of the open top of the box, and a pair of doors hinged upon the base and arranged in a plane side by side and substantially close together, and having a relatively large sight-opening in each thereof, 40 said doors being of such area as to overlie the door openings respectively, each of said sight openings being covered with substantially transparent material. 45

3. A display cover for a relatively long open-top box of the character described comprising in combination a substantially flat sheet-metal base of relatively long and narrow side and end parts arranged to conform in shape to the top of the box and adapted to rest upon the top edges thereof, 50 said base having continuous depending flanges at its outer edges adapted to encompass the outer surfaces of the box near the top thereof and to telescope therewith in readily attachable and detachable relation, 55 said base parts defining an open interior substantially the area of the open top of the box, and a pair of doors with a relatively large sight-opening in each thereof normally overlying the open interior of the base, each of said sight openings being covered 60 with substantially transparent material, said doors being respectively hinged upon the base at opposite ends of the base, the sides of the doors opposite the hinges respectively being substantially close to each other when 65 the doors are closed. 70

JACOB I. RUSSAKOV.
